UNITED STATES PATENT OFFICE

PHILIP W. MOORE, OF HUBBARD WOODS, ILLINOIS, ASSIGNOR TO THE P & M COMPANY,
OF CHICAGO, ILLINOIS, A CORPORATION OF ILLINOIS

RAIL ANCHOR

Application filed June 5, 1930. Serial No. 459,304.

This invention relates to devices for resisting longitudinal creeping movements of railroad rails and especially to devices of the above general character adapted to be secured to a railroad rail in a position to abut against a stationary part of the roadbed.

The principal object of the invention is to provide a simplified device which can be made very cheaply, easily applied to the rail, and which will maintain a firm hold on the rail when in its applied position.

A more specific object is to provide a rail anchor device made of resilient material and so formed that the resilient qualities of the metal serve to maintain the rail engaging portions at a suitable angle to the bottom surface of the rail base so as to effect a shackle grip on the top and bottom surfaces of the rail, which shackle grip will be increased when the rail anchor is forced against an adjacent cross tie by the longitudinal creeping movement of the rail.

A further specific object is to provide a one-piece rail anchor in the form of a clip having spaced arms recessed to receive one edge of the base flange of a rail, which arms are resilient and so disposed with relation to each other that it is necessary, in applying the device to the rail to flex the arms longitudinally of the rail, whereby upon release of the arms the reflex of the metal moves the rail gripping portion of the clip into spring gripping engagement with the top and bottom surfaces of the rail base.

A further object of the invention is to provide a clip of the above character which can be applied to either side of a railroad rail and which may be applied to bear against either of two adjacent ties so as to resist longitudinal creeping movement of the rail in either direction.

The invention has for a still further object such other new and improved constructions in rail anchoring devices hereinafter described and claimed for carrying out the above mentioned objects or such other incidental objects as will appear from a detailed description of the invention.

In the drawings:

Fig. 1 is a fragmentary side view of the

base portion of a railroad rail and a cross tie showing a rail anchor device constructed in accordance with my invention applied to one base flange of the rail in a position to bear against the said cross tie.

Fig. 2 is a view similar to Fig. 1 showing the device of my invention flexed to an initial position to permit it to be applied to the base flange of a rail.

Fig. 3 is a view in perspective of the form of rail anchor device illustrated in Figs. 1 and 2.

Fig. 4 is a view similar to Fig. 1 showing a modified form of rail anchor applied in its operative position to the base flange of a railroad rail; and

Fig. 5 is a view in perspective of a modified construction shown in Fig. 4.

Referring first to Figs. 1, 2 and 3 of the drawings:

The anchor shown in these figures consists of a U-shaped clip, the arms 10 and 11 of which are formed with recesses 12 and 13 adapted to receive the marginal portion of one base flange 14 of a rail. The bend 15 of the clip is preferably of such size as to permit normal flexing of the arms longitudinally of the rail without over-stressing of the metal and also maintain the arms normally in spaced relation to each other when the clip is in its applied position. The recesses 12 and 13 provide each arm of the clip with upper and lower jaws 16 and 17 and 18-19, respectively. The rail engaging surfaces of the jaws of one arm extend at an angle to the corresponding surfaces of the jaws of the other arm so that a projection of their planes intersect each other intermediate the arms as illustrated at A and B in Fig. 1. This angular disposition of the jaws is provided

preferably, though not necessarily, by forming the walls of said recesses at substantially right angles to the side planes of the arms, and then so bending the clip that the arms 10-11 normally converge toward their upper ends when the clip is free of the rail. The recesses 12-13 are preferably of such size that they will receive the flange 14 of the rail only when the arms 10-11 are moved toward a position perpendicular to the bottom

surface of the rail base—that is to say, by a movement of the arm tending to move the recesses into horizontal alignment. In the latter position of the arms, the clip may be moved transversely of the rail base so that the jaws embrace the marginal portion of the base flange 14 at locations spaced longitudinally of the rail. The reflex of the metal of the clip, the clip being preferably spring steel, tends to move the clip arms toward the angular positions from which they were sprung and consequently tends to move the edges 16^a—18^a of the upper jaws and the edges 17^a—19^a of the lower jaws into spring gripping engagement with the top and bottom surfaces of the rail base. After the jaws have been moved into their rail flange embracing position the flexing pressure on the jaws is released, whereupon the reflex action of the metal moves the arms longitudinally of the rail toward the position from which they were sprung. The amount of this longitudinal reflex movement of the arms depends upon the size of the recesses 12—13 relative to the thickness of the base flange 14 embraced. Preferably, the size of said recesses is such as to permit the return of the arms to an angular position as shown in Fig. 1. In such position of the arms of the clip, the lower portion of the clip bears against the vertical face of an adjacent cross-tie 20. Consequently any creeping movement of the rail in the direction indicated by the arrow in Fig. 1, exerts pressure on the lower portion of the clip and tends to increase the shackle or lever grip of jaws 16—17 on the top and bottom surfaces of the base flange 14 of the rail. Movement of the rail in the opposite direction, while holding the lower portion of the clip against movement, increases the grip of jaws 18—19 on the rail.

The arms 10—11 of the clip may be spread apart, preliminary to the application of the clip to the base flange of a rail, by driving a wedge between said arms or by the use of any other suitable spreading implement.

Figs. 4 and 5 illustrate a modified construction. The modified construction, however, is of the same general type as the clip shown in Figs. 1 to 3 inclusive except that the arms 21—22 of the clip normally diverge toward their upper ends instead of converging as illustrated in the preceding figures. In the modified embodiment the arms 21—22 are moved toward each other to bring the arms into a position perpendicular to the bottom surface of the rail base substantially as shown in Fig. 2, and the reflex of the metal, upon releasing said jaws, moves them longitudinally of the rail until they assume the position shown in Fig. 4. In this position it will be seen that the upper and lower jaws 23—24 and 25—26 are moved into spring shackle gripping engagement with the top and bottom surfaces of the rail base. The

arm 22 bears against the adjacent cross tie and due to the angular position of the arm increases the gripping action of jaws 25—26 on the rail base when the rail tends to creep in the direction indicated by the arrow. Reverse creeping movements of the rail increase the grip of the jaws 23—24 in the same manner as described in connection with the construction shown in Figs. 1 to 3 inclusive.

While I have described my invention in connection with two specific embodiments, it will be obvious to those familiar with this art that other modifications will readily suggest themselves. It will be understood therefore that I contemplate all such modifications as come within the scope of the appended claims.

I claim:

1. A rail anchor comprising a substantially U-shaped clip formed with upturned arms having recesses near their upper ends to receive one flange of a rail base, said upturned arms being formed to normally stand at an angle to each other when the anchor is free of the rail and the walls of each of said recesses being substantially perpendicular to the side plane of the upturned arm in which the recess is formed, whereby said upturned arms of the clip must be flexed longitudinally of the rail to bring the walls of said recesses into horizontal alignment with the top and bottom surfaces of the base flange of the rail prior to engagement of the clip over the said base flange.

2. A rail anchor comprising a clip formed of plate steel bent to provide upturned arms disposed edgewise to the base flange of the rail and recessed to provide each upturned arm with an upper and a lower jaw for gripping the upper and lower surfaces of one base flange of a rail, said recesses being of such size and said arms being disposed at an angle to each other whereby it is necessary, preliminary to engagement of the clip over the base flange of the rail, to flex the said arms of the clip longitudinally of the rail.

3. A rail anchor comprising a flat spring metal member bent to form a U-shaped clip having spaced upturned arms each arm being provided with a recess adapted to receive the edge portion of one flange of a rail, the said arms being disposed at an angle to each other and the said recesses being formed of such size that it is necessary to move said arms toward a position perpendicular to the bottom surface of the rail base flange preliminary to applying the clip on said flange, the reflex of said arms toward the position from which they were sprung serving to hold said arm portions in shackle gripping engagement with the top and bottom surfaces of said base flange.

4. A rail anchor comprising a U-shaped clip formed with upturned arms which converge toward their upper ends and are re-

cessed to provide jaws for gripping the top and bottom surfaces of one base flange of a rail, the recesses being so positioned in said converging arms that the arms must be flexed longitudinally of the rail preliminary to the application of said jaws over the rail base flange whereupon the reflex of the arms, when released from said preliminary flexing, move the arms to angular positions relative to the rail base to exert shackle grips on the base.

5. A rail anchor comprising a clip made from plate spring metal bent to a U-shape to form upturned arms which diverge toward 15 their upper ends and recessed to provide jaws for gripping the top and bottom surfaces of one base flange of a rail, the recesses being so disposed in said diverging arms that the arms must be flexed toward each other preliminary 20 to application to said jaws over the rail base flange.
